US0D1056487S

(12) **United States Design Patent** (10) **Patent No.:** **US D1,056,487 S**
(45) **Date of Patent:** **** Jan. 7, 2025**

(54) **STORAGE CHEST**

- (71) Applicant: **APEX BRANDS, INC.**, Apex, NC (US)
- (72) Inventors: **Richard A. Samsel**, Haines, FL (US); **Jonathan Ezequiel-Shriro**, St. Louis, MO (US); **Matthew Poppe**, Holly Springs, NC (US); **Jason Mars**, Jonesboro, AR (US); **Michael Taber**, Jonesboro, AR (US)
- (73) Assignee: **APEX BRANDS, INC.**, Apex, NC (US)

(**) Term: **15 Years**

(21) Appl. No.: **29/772,867**

(22) Filed: **Mar. 4, 2021**

(57) **CLAIM**

The ornamental design for a storage chest, as shown and described.

DESCRIPTION

FIG. 1 is a perspective front view of a storage chest in accordance with the present design; FIG. 2 is a front view of the storage chest of FIG. 1; FIG. 3 is a rear view of the storage chest of FIG. 1; FIG. 4 is a right side view of the storage chest of FIG. 1; FIG. 5 is a left side view of the storage chest of FIG. 1; FIG. 6 is a top view of the storage chest of FIG. 1; and, FIG. 7 is a bottom view of the storage chest of FIG. 1. Any broken lines of the storage chest in FIGS. 1-7 are illustrative of portions of the storage chest that form no part of the claimed design.

1 Claim, 7 Drawing Sheets
